(Cl. D87—3)

To all whom it may concern:

Be it known that we, William A. Pence and Leslie S. Spielmann, citizens of the United States, residing respectively at Adell, in the county of Sheboygan and State of Wisconsin, and West Bend, in the county of Washington and State of Wisconsin, have invented a new, original, and ornamental Design for a Billfold, of which the following is a specification, reference being had to the accompanying drawing, forming part thereof.

In the drawing:

Fig. 1 is a view in elevation of the inner face of a billfold showing our new design.

Fig. 2 is a view in elevation of the outer face of the billfold in Fig. 1.

We claim:

The ornamental design for a billfold as shown.

WILLIAM A. PENCE.

LESLIE S. SPIELMANN.
